UNITED STATES PATENT OFFICE.

PAUL J. EKLUND, OF MINNEAPOLIS, MINNESOTA.

GARMENT-SUPPORTER.

973,017.

Specification of Letters Patent. Patented Oct. 18, 1910.

Application filed May 25, 1909. Serial No. 498,323.

To all whom it may concern:

Be it known that I, PAUL J. EKLUND, a citizen of the United States, residing at Minneapolis, in the county of Hennepin and State of Minnesota, have invented certain new and useful Improvements in Garment-Supporters, of which the following is a specification.

This invention relates to an improved 10 garment supporting device which is specially adapted for the use of boys and youths, although it is by no means limited to such use inasmuch as it may be found to be extremely useful by bicyclists and other 15 sportsmen who affect the use of knickerbockers and long stockings.

The invention has for its object to provide in a single organized device supporting means for the trousers or knickerbockers 20 as well as for the stockings; the device being so constructed and arranged that dressing and undressing shall be greatly facilitated; that the stocking support may be separately cast off or detached; that the 25 trousers' support may likewise be separably cast off or detached and that when desired the stocking support may remain connected with the supporting means for the front of the trousers when cast off, thus preventing 30 the loss of parts of the device by causing the several parts to remain connected with the stockings and the trousers when the garments are removed.

Further objects of the invention are to 35 provide a device of the character described which shall possess superior advantages in point of simplicity, durability and general efficiency; and with these and other ends in view which will readily appear as the nature 40 of the invention is better understood, the invention consists in the improved construction and novel arrangement of parts which will be hereinafter fully described and particularly pointed out in the claim.

45 In the accompanying drawing has been illustrated a simple and preferred form of the invention; it being, however, understood that no limitation is necessarily made to the precise structural details therein exhibited, 50 but that changes, alterations and modifications within the scope of the claim, may be resorted to when desired.

In the drawing—Figure 1 is a front view, 55 partly in perspective, of a garment supporting device constructed in accordance with the invention. Fig. 2 is an enlarged longi-

tudinal section produced through one of the garment-supporting members. Fig. 3 is a detail view showing the trousers cast-off as it appears when the parts are separated. 60 Fig. 4 is a detail view showing the stocking cast-off, detached, and related parts. Fig. 5 is a detail view showing a portion of the stocking with its supporting device detached from the suspender strap. 65

Corresponding parts in the several figures are denoted by like characters of reference.

The suspender straps 6—6 are crossed diagonally at the back, being connected at the points of intersection by suitable connecting means such as stitching 7. The rear ends of the suspender straps have been shown equipped with button-hole tabs 8 of ordinary construction. The forward ends of the suspender straps are doubled upon themselves and form loops 9 the front terminals of said straps being connected with the bodies of the straps by buckles 10 which permit the loops to be lengthened or shortened, thus providing means whereby the effective 70 length of the straps may be regulated in a manner which is well known in suspenders and allied supporting devices. 75

Each of the loops 9 supports an elongated link 11 which is utilized for the purpose of attaching a cast-off member A, constructed of sheet metal or other suitable material, and comprising a front plate 12 having slots 13 and provided at its lower end with a hook 14, and a resilient tongue 15 extending downwardly from the upper end of the plate to a point below the bill of the hook, and having terminal lugs 16 adapted to work in the slots 13. The construction of the cast-off here briefly described and illustrated in 80 the drawing, is not included in the present invention, but simply represents an article which may be purchased in the open market and which has been utilized in the construction of the improved article. It may here be 85 appropriately stated that the remaining cast-offs as well as the links, buckles, stocking supporters and other parts used in the construction of the device, may be purchased in 90 the open market; the present invention depending for novelty upon the peculiar and novel arrangement, assemblage and combination of the component parts. 95

B—B designate stocking supporting straps, preferably made of elastic material 100 and provided at their upper ends with turned-over and securely stitched portions 110

forming loops 17; the lower ends of said straps being doubled upon themselves to form loops 18 the length of which may be adjusted by means of buckles, 9^a. The loops 5 17 at the upper ends of the straps B are equipped with links 19 and 20. The links 19 extend upwardly from the straps B and are connected with the hooks 14 of the cast-offs A, being securely retained in said hooks 10 by means of the terminal lugs 16 of the resilient tongues 15; it being, however, evident that by pressing the resilient tongues so as to project the lugs 16 through the slots 13, the links 19 may be readily separated or detached 15 from the hooks. The links 20 extend downwardly in front of the straps B and are equipped with cast-offs C of ordinary well known construction for the straps 21 having terminal button-holes 22 for connection 20 with the buttons upon the front of the trousers. The loops 18 at the lower ends of the straps B carry links 23 which serve for the attachment of suitable cast-offs 24 having terminal hooks 25 at their upper ends 25 whereby they may be detachably connected with the links 23, said cast-offs being also provided with resilient tongues 26 engaging the hooks so as to prevent accidental detachment. The lower ends of the cast-offs 24 30 are equipped with links 27 carrying stocking supporters 28 of ordinary well known construction.

From the foregoing description taken in connection with the drawings hereto annexed, the operation and advantages will be readily understood. When the improved garment supporter is adjusted across the shoulders of the wearer, the tabs 8 are connected in the usual manner with the buttons 35 upon the rear portion of the trousers' band after which the button-hole tabs 22 are likewise connected with the buttons upon the front portion of the band. The straps B—B are permitted to depend inside the trousers' 40 leg, the stocking supports 28 having been previously detached by disconnecting the cast-offs 24 from the links 23, if desired. This permits the stocking supports to be connected with the stockings without any 45 straining or effort on the part of the wearer, and the cast-offs may afterward be very readily connected with the links 24. It will be seen that the arrangement herein described permits the trousers to be loosened by 50 unbuttoning the tabs 8 and disconnecting the front portion by disengaging the straps 21 from the cast-offs C; the wearer may thus assume a sitting posture without disconnecting the stocking supporting members of the 55 device. When undressing, the cast-offs 24 may be disengaged from the links 23, thus leaving the supporters 28 connected with the stockings and saving the wear upon the 60

stockings, which is caused by the frequent detachment and replacement of the supporting members; or, if desired, the links 19 65 may be detached from the cast-offs 12, thus leaving the suspending straps B connected with the stockings.

It will be seen that the arrangement herein 70 described permits the trousers to be loosened by unbuttoning the tabs 8 and disconnecting the front portion by disengaging the links 19 from the cast-off 12 (the suspending strap B being upheld by loops 21 which remain connected) thus allowing the wearer 75 to assume a sitting posture without disarranging the position of suspenders on shoulder and greatly facilitating reconnection of tabs 8 to trousers. When undressing, the 80 straps 21 may be disengaged from cast-offs C and the links 19 from cast-offs 12 leaving the suspending straps B connected with stockings; so that in dressing, the links 19 may be attached to buckles A while wearer 85 is standing in upright position and trousers are drawn fully on. Also if desired, the cast-offs 24 may be disengaged from the links 23, thus leaving the supporters 28 connected with the stockings and saving the 90 wear upon the stockings, which is caused by the frequent detachment and replacement of the supporting members; or, if desired, the links 19 95 may be detached from the cast-offs 12, thus leaving the suspending straps B connected with the stockings.

Having thus described the invention, what is claimed is:

In a device of the kind described, a pair of suspender straps, a second pair of straps, 100 engaging means carried by the forward ends of the first pair of straps to detachably connect said forward ends with the respective upper ends of the second pair of straps, a cast off fixed to each of the second pair of 105 straps adjacent its upper end, a trousers supporter carried by each cast off, a pair of stocking supporting devices, and engaging means carried by the stocking supporting devices to detachably connect the stocking 110 supporting devices to the lower ends of the second pair of straps, said trousers supporters and stocking supporting devices being connected to the suspender straps solely through the second pair of straps whereby 115 respective trousers supporters and stocking supporting devices may remain connected when the second pair of straps are disconnected from the suspender straps.

In testimony whereof I affix my signature 120 in presence of two witnesses.

PAUL J. EKLUND.
